Primary Examiner—Alan P. Douglas*Assistant Examiner*—M. N. Pandozzi*Attorney, Agent, or Firm*—Price, Heneveld, Cooper, DeWitt & Litton[57] **CLAIM**

The ornamental design for the drinking cup for children, as shown and described.

DESCRIPTION

FIG. 1 is a top perspective view of the drinking cup for children showing my new design;

FIG. 2 is a left side elevational view of FIG. 1, the right side elevational view being a mirror image of that shown;

FIG. 3 is a front elevational view of FIG. 1;

FIG. 4 is a rear elevational view of FIG. 1;

FIG. 5 is a top plan view of FIG. 1;

FIG. 6 is a bottom plan view of FIG. 1;

FIG. 7 is a top perspective view of a second embodiment of the drinking cup for children;

FIG. 8 is a left side elevational view of FIG. 7, the right side elevational view being a mirror image of that shown;

FIG. 9 is a front elevational view of FIG. 7;

FIG. 10 is a rear elevational view of FIG. 7;

FIG. 11 is a top plan view of FIG. 7; and,

FIG. 12 is a bottom plan view of FIG. 7.
